To all whom it may concern:

rounded by emblematic symbols arranged as to produce an open-work design.
In the accompanying photograph and tracing at the top of the frame, it is a classurrounded by a cloud 2, inscribed with heraldic arms, beneath the cross 1, are a square 3, and compass 4, which enclose a double cross 5, beneath the square and compass being part of the frame, is a Maltese cross 6. On one side of the square and compass cross words, and a nine pointed star 7, upon which is a cross 8, and upon the cross 9, a serpent 10; on the other side of the square and compass is a tent 11, and a nine pointed star 12, and a cross 13, and upon the cross 13, a serpent 14, the whole being supported by ornamental scroll work. At the bottom centre of the frame 15, is a circular gay within which is a crown 16, and a Christian cross 17, there being on the right of the gay 15, a bangle 18, and on the left a bangle 19, both being enclosed in scroll work. On one side of the frame 20, is a pillar 20, to which is added a "Chapiter" 21, and on the top of the chapiter is placed a globe 22, on the other side is a pillar 23 placed a globe 25.
